CLAIM

We claim the ornamental design for a plug adaptor, as shown and described.

DESCRIPTION

FIG. 1 is a front perspective view of a plug adaptor;

FIG. 2 is a back perspective view of the plug adaptor;

FIG. 3 is a top plan view thereof;

FIG. 4 is a bottom plan view thereof;

FIG. 5 is a left elevational view thereof;

FIG. 6 is a right elevational view thereof;

FIG. 7 is a back plan view thereof; and,

FIG. 8 is a front plan view thereof.

The broken line portion of the figure drawings is included to show unclaimed subject matter only and forms no part of the claimed design.
